UNITED STATES PATENT OFFICE.

ALTON A. ALLEN, OF FALL RIVER, MASSACHUSETTS.

SURF-BOAT.

1,323,732.

Specification of Letters Patent.

Patented Dec. 2, 1919.

Application filed November 29, 1918. Serial No. 264,589.

To all whom it may concern:

Be it known that I, ALTON A. ALLEN, a citizen of the United States of America, and resident of Fall River, in the county of 5 Bristol and State of Massachusetts, have invented new and useful Improvements in Surf-Boats, of which the following is a specification.

This invention relates to a boat adapted 10 to be used by bathers in floating or swimming or riding waves and the object of the invention is to provide a boat of this character which is light and buoyant, which can be easily and substantially constructed, 15 which is adapted comfortably to support a bather either partially or wholly in swimming or floating, which is adapted to skim over the water with a minimum of resistance, which can be used in any one of a 20 number of positions so as to minimize the inconvenience of turning the boat properly to position same relatively to the bather, which will remain water-tight with little or no calking, which will have little tendency 25 to stick to the sand when left on the beach, and which has any one of the aforesaid characteristics or any two or more of the aforesaid characteristics in combination.

The invention consists primarily in a 30 buoyant body peculiarly shaped to adapt itself to assist a bather in swimming or floating. The upper surface of the body is sloped downwardly toward one end to permit a bather to lie face downwardly on the 35 said end with his legs extending beyond the end and the body is preferably made sufficiently narrow to permit the bather when lying in said position to use his arms on opposite sides of the boat in swimming. 40 The lower surface of the body is sloped upwardly toward the opposite end to cause the boat to skim over the water, with less resistance. In order to adapt the boat to be used in any position, with either end foremost and with either side up, the upper surface is sloped downwardly in the aforesaid manner at both ends and the lower surface is sloped upwardly in the aforesaid manner at both ends, preferably so that the 45 upper and lower surfaces substantially meet at an edge at both ends and so that the boat is symmetrical with respect to its central horizontal plane. The sloping portions of the said surfaces may be either curved or 50 flat and they may extend either a part or all of the way to the center of the boat, but

they are preferably curved and they preferably extend substantially to the center of the boat so that the upper and lower surfaces of the boat respectively curve upwardly and downwardly substantially continuously from one end to the other. In this way the upper and lower walls of the boat may be applied to the frame more easily and tightly when constructing the 60 boat in the particular manner hereinafter described, and the boat has less tendency to stick to the sand when left on the beach owing to the fact that the curved wall resting on the sand contacts with the sand only 70 throughout a limited area. This is of particular importance when the sand is wet inasmuch as a flat body resting on wet sand sticks tightly to the sand due to the fact that the water rises in the sand and fills the spaces 75 between the particles of sand and the body.

In a more specific aspect the invention comprises a hollow body having its upper and lower walls (shaped in the aforesaid manner) closed at the sides and ends to 80 form a substantially water-tight compartment therein. The upper and lower walls are preferably formed of transverse boards fitted tightly together and secured to side and end members as will hereinafter be described more in detail.

In the accompanying drawings illustrating the preferred embodiment of my invention,

Figure 1 is a perspective view of the boat; 90

Fig. 2 is a plan view of the boat, constructed as hereinafter described;

Fig. 3 is a side elevation of the boat;

Fig. 4 is a vertical horizontal section on line 4—4 of Fig. 2; and 95

Fig. 5 is a perspective view of the frame of the boat, one end of the frame being broken away.

As illustrated in Fig. 1, my improved boat is preferably considerably longer than wide 100 and considerably wider than thick. As above stated the upper and lower surfaces 1 are preferably curved longitudinally of the boat so as to meet at the ends 2 and 3 which are preferably rounded both about horizontal axes and at the corners. As illustrated the transverse elements of the top and bottom surfaces are preferably straight so as to minimize the tendency of the boat to tip laterally. The sides 4 are preferably 110 flat as illustrated, although this particular shape of the sides is not essential.

My preferred construction comprises side members 5 which taper longitudinally toward each end as illustrated in Fig. 5. Extending between the ends of the side members 5 are end members comprising outer portions 7 and inner portions 8. The outer portions 7 overlap the ends of the side members 5 and the inner portions 8 extend inwardly into the space between the ends of the side members. The inner portions 8 of the end members fit against the inner sides of the side members at their opposite ends and are tapered longitudinally of the side members so that their upper and lower surfaces are flush with the upper and lower surfaces of the side members. The outer and inner portions of the end members are defined from each other by shoulders 9 disposed substantially in the planes of the ends of the side members. The depth of the shoulders 9 is made equal to the thickness of the upper and lower walls of the boat. The outer portions 7 of the end members are also tapered longitudinally of the boat so that the upper and lower surfaces of the portions 7 are substantially continuous with the outer surface of the walls of the boat. The portions 7 of the end members are rounded at their outer edges and are also rounded at their ends. The upper and lower walls of the boat are preferably formed of transverse boards 10 fitted tightly together and secured at their opposite ends to the side members 5. As illustrated in Fig. 4 the boards 10 lap over the inner portions 8 of the end members and fit against the shoulders 9 of the end members. Owing to the tapered shape of the inner portions 8 of the end members they are held in position by the boards 10 when the boards 10 are merely secured to the side members. However, in order to tie the parts together more securely the boards overlapping the inner portions 8 of the end members are also preferably secured directly to the portions 8.

In order to drain from the interior of the boat any water which may leak thereinto I preferably provide an opening 11 at one corner of the side members at one corner of the boat. It will of course be understood that the opening 11 is normally plugged and that water is drained from the boat by removing the plug and tipping the boat so that the water will run to the corner in which the opening 11 is provided.

In using my improved boat the bather rests his body on one end of the boat face downwardly with his legs extending beyond the end of the boat and with his arms either resting on the boat or extending into the water on opposite sides of the boat. Owing to the curved contour of the upper surface of the boat it affords a comfortable rest for the bather and owing to the rounded ends and corners there is little danger of injury. It will be understood that the boat is approximately as long as the average bather and that when resting on the boat in the aforesaid manner the bather's head is in the central region of the boat. Thus the forward end of the boat will be tipped up and owing to the curvature of the lower surface of the boat it can be propelled over the water with a minimum of resistance. By curving the upper and lower surfaces of the boat at both ends the bather may rest his body on the boat in the aforesaid manner in any one of four positions of the boat, viz., at either end of the boat and with either side of the boat uppermost. In approaching the boat, therefore, it is never necessary to turn it over or turn it end for end. The boat is preferably made sufficiently buoyant to support the entire weight of the bather so that he may, if he desires, sit or lie upon the boat. Owing to the peculiar construction of the end members and their unique association with the side members and upper and lower walls unusually tight and permanent joints are formed at the ends of the boat.

I claim:

1. A surf boat comprising a buoyant body having side members vertically tapered from their central region toward each end, end members uniting the ends of said side members to form a substantially rectangular frame, and flat surface members covering each face of said frame. 100

2. A surf boat comprising a buoyant body having side members vertically tapered from their central region toward each end, end members uniting the ends of said side members so as to form a substantially rectangular frame, and straight sheathing members extending transversely of said frame on each face thereof and inclosing said frame. 105

Signed by me at Fall River, Massachusetts, this 25th day of November, 1918.

ALTON A. ALLEN.
